UNITED STATES PATENT OFFICE

2,003,800

OFFSET PRINTING PRESS

Howard M. Barber, Pawcatuck, Conn., assignor
to C. B. Cottrell & Sons Company, Westerly,
R. I., a corporation of Delaware

Application August 1, 1934, Serial No. 737,892

36 Claims. (Cl. 101—177)

This invention is directed to that type of offset web printing presses in which a plurality of printing units are used, each printing unit comprising a common impression cylinder and pairs of design and transfer cylinders, their inking mechanisms, and with or without moistening mechanisms; said printing units operating in unison with a suitable web advancing means such, for instance, as a folder, delivery, feeder, or two or more combined.

This invention consists, generally, in a common drive for the web advancing means and the printing units and a separate drive for the pairs of design and transfer cylinders of each printing unit, means being provided for permitting the driving or stopping of the web advancing means and the impression cylinders independently of the pairs of design and transfer cylinders and for permitting the driving or stopping of the said pairs of design and transfer cylinders independently of the web advancing means and impression cylinders.

This invention consists, more particularly, in the provision of one motor operable to drive the printing units and web advancing means or to drive the web advancing means and the impression cylinders of the printing units, and auxiliary motors for driving the pairs of design and transfer cylinders independently of their impression cylinders and web advancing means, means being provided for bringing the first named motor into and the other motors out of operative connection with the pairs of design and transfer cylinders.

This invention consists, still more particularly, in means for separating the design and transfer cylinders of each pair without operatively disconnecting them; means for separating the transfer and impression cylinders without operatively disconnecting them; and means for operatively disconnecting the transfer and impression cylinders without operatively disconnecting the impression cylinders from the web advancing means.

The object of my invention is to provide a multicolor offset printing press of the above character whereby the press crews may work independently upon either the web advancing means and its operatively connected impression cylinders when they are disconnected from their pairs of design and transfer cylinders; or independently upon the pairs of design and transfer cylinders and their inking and moistening mechanisms. Thus, the web may be threaded and advanced through the press and into the folder, if

one is employed, without stopping the pairs of design and transfer cylinders; also the pairs of design and transfer cylinders and the inking and moistening mechanisms may be independently worked upon for various purposes, as for applying a plate to any one or more of the design cylinders or for preparing and adjusting the inking and moistening mechanisms, or for gumming the design cylinders, without affecting the running or stopping of the web advancing means and impression cylinders; thereby permitting the press crews to work on the independently operating parts at the same time and thus materially shorten the period consumed for bringing the press into its full printing condition.

A practical embodiment of my invention is represented in the accompanying drawings which illustrate a four color offset web printing press.

Figs. 1 and 1a represent a detail top plan view of the printing press, the several coacting levers being omitted for sake of clarity.

Figs. 2 and 2a represent a detail side view of the press showing in diagram the printing units, the web and the web advancing means.

Figs. 3 and 3a represent a detail side view of the printing units, showing the gearing through which the web and the several cylinders are driven.

Figs. 4 and 4a represent a detail side elevation of the printing unit illustrated in Fig. 3, showing the various control levers in their respective positions when the common impression cylinder and the two pairs of design and transfer cylinders are contacting and interconnecting and the press is running at full speed.

Figs. 5 and 5a represent a similar view of the printing unit illustrated in Fig. 3a.

Figs. 6 and 6a represent a similar view of the printing unit illustrated in Fig. 3, showing the various control levers in their respective positions when the common impression cylinder and the two pairs of transfer cylinders are separated and operatively disconnected, the design and transfer cylinders being in contact and operatively connected, and the inking and moistening mechanisms being in contact with the design cylinders; to permit coactive movement of the design and transfer cylinders independently of their common impression cylinder and of the web advancing means, and vice versa.

Figs. 7 and 7a represent a similar view of the other printing unit illustrated in Fig. 3a.

Figs. 8 and 8a represent a similar view of the printing unit illustrated in Fig. 3, showing the various control levers in their respective posi-

tions when the inking mechanisms are out of contact with their design cylinders, the design cylinders out of contact with their transfer cylinders, and the transfer cylinders out of contact and operatively disconnected from their common impression cylinder.

Figs. 9 and 9a represent a similar view of the other printing unit represented in Fig. 3a.

Fig. 10 represents a detail vertical cross section 10 on an enlarged scale, taken in the plane of the line X—X of Fig. 1, looking in the direction of the arrows.

Fig. 11 represents an enlarged central section 15 through one of the magnetic clutches which control the operative connection and disconnection of the transfer and impression cylinders.

Fig. 12 represents a central section on the same 20 scale as Fig. 11, of one of the magnetic clutches for controlling the operative connection and disconnection between one of the drives and its pairs 25 of design and transfer cylinders.

Figs. 13 and 13a represent the wiring diagram of the operating control for the various mechanisms.

The two color web printing units illustrated 25 herein each comprises a common impression cylinder and two pairs of design and transfer cylinders operatively connected therewith, the four design cylinders being denoted by 1, 2, 3, 4, the four transfer cylinders by 5, 6, 7, 8 and the two impression cylinders by 9, 10. The shafts of the design cylinders are denoted by 11, 12, 13, 14, the shafts of the transfer cylinders by 15, 16, 17, 18, and the shafts of the impression cylinders by 19, 20.

30 The inking mechanisms for the two printing units comprise, generally, the ink fountains 21, 22, 23, 24, the fountain rolls 25, 26, 27, 28, the fountain roll clutches 29, 30, 31, 32, the ductor roll 33, 34, 35, 36, the distributing rolls 37, 38, 39, 40, and the design cylinder inking rolls 41, 42, 43, 44.

35 The moistening mechanisms for the two printing units comprise, generally, the fountains 45, 46, 47, 48, the fountain rolls 49, 50, 51, 52, the ductor rolls 53, 54, 55, 56, and the design cylinder water applying rolls 57, 58, 59, 60.

40 The web is denoted by 61 and it leads from its supply roll 62 to and around the impression cylinders 10, 9 and from thence to a delivery which, in the present instance, is shown as a folder 63. The web advancing means includes the folder 63 and also the web supply roll drive which is herein shown as an endless tape carrier 64 engaging the periphery of the web supply roll 62 and passing around pulleys 65, 66, interconnected by a train 45 of gears 67, 68, 69, 70, 71.

45 Three motors are provided, the main motor 72 being arranged to either drive the web advancing means and the printing units, or the web advancing means and the impression cylinders of the printing units independently of the remainder of the printing units; and the auxiliary motors 73, 74 being arranged to independently drive the remainders of their respective printing units, i. e., the pairs of design and transfer cylinders and their inking and moistening mechanisms.

50 The drive from the main motor 72 to the web advancing means, i. e., the folder 63 and the web supply roll drive comprises the following elements:

55 The shaft 75 of the main motor 72 is provided with a pulley 76 which drives through a belt 77 a pulley 78 of a longitudinally disposed shaft 79. A bevel gear 80 on the shaft 79 drives a bevel gear 81 on the upright shaft 82 of the folder 63. An-

other bevel gear 83 on the shaft 79 drives a bevel gear 84 on the cross shaft 85, which cross shaft drives, through a train of gears 86, 87, 88, 89 the shaft 90 on which the pulley 65 and gear 67 are mounted.

5 The drive from the main motor 72 to the impression cylinder shafts 19, 20 of the two printing units, is as follows:

Bevel gears 91, 92 on the longitudinally disposed shaft 79 drive bevel gears 93, 94 on cross shafts 95, 96, bearing gears 97, 98 which mesh with gears 99, 100, loosely mounted on cross shafts 101, 102. These loose gears 99, 100 drive gears 103, 104 fast on the impression cylinder shafts 19, 20.

15 The drives from the auxiliary motors 73, 74 to the shafts 19, 20 of the impression cylinders 9, 10 are as follows:

The shafts 105, 106 of the auxiliary motors 73, 74 drive the cross shafts 101, 102, through reduction gear units 107, 108, their shafts 109, 110, and magnetic clutches 111, 112, gears 113, 114 fast on the cross shafts 101, 102 drive the gears 115, 116, loosely mounted on the impression cylinder shafts 19, 20.

20 Magnetic clutches 117, 118 are provided for interlocking and releasing the fast gears 103, 104 of the main motor drive, and the loose gears 115, 116 of the auxiliary motor drives, which gears are on the impression cylinder shafts 19, 20, 30 respectively.

25 The drives from the impression cylinder shafts 19, 20 to their transfer cylinder shafts 15, 16, 17, 18 and design cylinder shafts 11, 12, 13, 14 respectively, and to the inking and moistening 35 mechanisms for the design cylinders 1, 2, 3, 4 of the two printing units, are as follows:

The loose gears 115, 116 on the impression cylinder shafts 19, 20 drive gears 119, 120, 121, 122 fast on the transfer cylinder shafts 15, 16, 17, 18. 40 Gears 123, 124, 125, 126 also fast on the transfer cylinder shafts 15, 16, 17, 18 respectively, drive gears 127, 128, 129, 130 fast on the design cylinder shafts 11, 12, 13, 14. These gears 127, 128, 129, 130 also drive the gears 131, 45 132, 133, 134 of the inking rollers 41, 42, 43, 44 respectively, and the gears 135, 136, 137, 138 of the moistening mechanisms. Gears 139, 140, 141, 142 fast on the design cylinder shafts 11, 12, 13, 14 drive gears 143, 144, 145, 146 which in turn drive 50 gears 147, 148, 149, 150 fast on the shafts 151, 152, 153, 154 of the ink fountain feed mechanisms.

The means for operating the inking mechanisms for both units are as follows:

55 Cams 155, 156, 157, 158 fast on the shafts 151, 152, 153, 154 respectively, act upon spring pressed rollers 159, 160, 161, 162, carried by arms 163, 164, 165, 166, fast on rock shafts 167, 168, 169, 170. Manually adjustable connections 171, 172, 173, 174 60 on the second arms 175, 176, 177, 178 fast on the rock shafts 167, 168, 169, 170 respectively, are provided for corresponding ends of connecting bars 179, 180, 181, 182, the other ends of which bars are connected to arms 183, 184, 185, 186 65 of the rock shafts 187, 188, 189, 190 respectively, of the fountain roll clutches 29, 30, 31, 32, to cause the fountain rolls 25, 26, 27, 28 to rotate, step by step. Hand screws 191, 192, 193, 194 are journaled in the arms 175, 176, 177, 178 respectively, and adjust the connections 171, 172, 173, 174 of the bars 179, 180, 181, 182 to control the movements of the fountain rolls 25, 26, 27, 28.

70 The design cylinders 1, 2, 3, 4 may be independently adjusted to bring them into proper 75

printing contact with their transfer cylinders 5, 6, 7, 8 as, for instance, by mounting the design cylinders on eccentric bearings 195, 196, 197, 198 respectively, adjustable rotatively by providing the bearings with arms 199, 200, 201, 202 from which rods 203, 204, 205, 206 extend to studs 207, 208, 209, 210 respectively, fixed to the press frame, where the rods may be screw-threaded and provided with adjusting nuts 211, 212, 213, 214, cooperating with the studs 207, 208, 209, 210; to move the rods 203, 204, 205, 206 longitudinally.

The transfer cylinders 5, 6, 7, 8 may be independently adjusted to bring them out of printing contact with their impression cylinders, for thickness of stock to be printed, without disturbing their printing contact with the design cylinders, and the transfer cylinders may also be independently adjusted to bring them out of printing contact with their design cylinders, when so desired. To accomplish these results the transfer cylinders are respectively mounted on outer and inner eccentric bearings 215, 216, 217, 218 and 219, 220, 221, 222.

Manual means for independently obtaining printing relation between each unit of design and transfer cylinders are as follows:

Hand levers 223, 224, 225, 226 are carried by rock shafts 227, 228, 229, 230 which are provided with eccentrics 231, 232, 233, 234 embraced by the upper members 235, 236, 237, 238 of connecting rods, the lower members 239, 240, 241, 242 of which are attached to the arms 243, 244, 245, 246 respectively, projecting from the outer eccentric bearings 215, 216, 217, 218 respectively.

Adjusting screws 247, 248, 249, 250 are provided between the members 235, 236, 237, 238 and 239, 240, 241, 242 respectively, of the connecting rods, to regulate the printing contact between the transfer cylinders 5, 6, 7, 8 and their impression cylinders 9, 10 when in printing position.

The transfer cylinders 5, 6, 7, 8 are independently adjusted to bring them out of contact with their design cylinders 1, 2, 3, 4, as well as their impression cylinders 9, 10, by providing the inner eccentric bearings 219, 220, 221, 222 with arms 251, 252, 253, 254, connected to corresponding ends of rods 255, 256, 257, 258, the other ends of which rods are attached to arms 259, 260, 261, 262 fast on rock shafts 263, 264, 265, 266 which are rocked from cams 267, 268 on the rotary cam shafts 269, 270, through the following connections:

Spring pressed studs or rollers 271, 272 are carried by arms 275, 276 of levers pivoted at 279, 280 respectively, second arms 283, 284 of which levers being yieldingly connected through rods 287, 288, 289, 290 with operating forked bars 291, 292, 293, 294 connected at their lower ends to arms 295, 296, 297, 298 of rock levers pivoted at 299, 300, 301, 302, the other arms 303, 304, 305, 306 of which levers are spring pressed and carry studs or rollers 307, 308, 309, 310 which respectively engage the peripheries of cams 311, 312 on the shafts 269, 270. The operating forked bars 291, 292, 293, 294 respectively, have shoulders 313, 314, 315, 316 and 317, 318, 319, 320 adapted to engage the pins 321, 322, 323, 324 and 325, 326, 327, 328 carried by rock levers 329, 330, 331, 332 fast on the rock shafts 263, 264, 265, 266. The rods 298, 299 are respectively connected to the forked bars 292, 294 through rock levers 333, 334 and their connecting bars 335, 336.

Means are provided for preventing the hand levers 223, 224, 225, 226 from being rocked except

under certain conditions to be hereinafter explained, which means are herein shown as comprising lock bars 337, 338, 339, 340, carried by the inner eccentric bearings 219, 220, 221, 222 in position to engage the diametrically opposed shoulders 341, 342, 343, 344 and 345, 346, 347, 348 respectively, carried by the said hand levers.

The rock levers 329, 330, 331, 332 have spring pressed connections at the pins 349, 350, 351, 352 with the lower ends of hook bars 353, 354, 355, 356, 357, 358, 359, 360 and 361, 362, 363, 364 respectively, arranged to engage their respective pins 365, 366, 367, 368 on the operating forked bars 369, 370, 371, 372 which are connected at their corresponding ends to the depending arms 373, 374, 375, 376 of rock levers pivoted at 377, 378, 379, 380 respectively, the uprising arms 381, 382, 383, 384 of which levers carry spring pressed rollers 385, 386, 387, 388 which ride on the faces of cams 389, 390, 391, 392 respectively, fast on the shafts 11, 12, 13, 14 of the design cylinders 1, 2, 3, 4.

The operating forked bars 369, 370, 371, 372 have two shoulders 393, 394, 395, 396 and 397, 398, 399, 400, arranged to alternately engage the pins 401, 402, 403, 404 and 405, 406, 407, 408 of rock levers 409, 410, 411, 412 fast on rock shafts 413, 414, 415, 416, which shafts are respectively provided with depending arms 417, 418, 419, 420 which are connected by rods 421, 422, 423, 424 to the depending arms 425, 426, 427, 428 of rock shafts 429, 430, 431, 432. These rock shafts have eccentrics 433, 434, 435, 436 forming supports for the end plates 437, 438, 439, 440 of the design cylinder inking roll carriages. These end plates carry pins 441, 442, 443, 444 for engagement with the lower ends of latch bars 445, 446, 447, 448 respectively, the upper ends of which latch bars have spring pressed lost motion connections with arms 449, 450, 451, 452 fast on rock shafts 453, 454, 455, 456. These rock shafts have fast thereon latch bars 457, 458, 459, 460 arranged to be brought into and out of engagement with the rock arms 175, 176, 177, 178, carried by the rock shafts 167, 168, 169, 170, the motion of which is controlled by the cams 155, 156, 157, 158 on the shafts 151, 152, 153, 154.

Overthrow hand levers are respectively pivoted at 461, 462, 463, 464, the handles being denoted by 465, 466, 467, 468. These hand levers are provided with arms 469, 470, 471, 472 having studs or rollers 473, 474, 475, 476, arranged to be brought into and out of contact with the operating forked bars 291, 292, 293, 294 respectively.

These overthrow hand levers are also provided with arms 477, 478, 479, 480 carrying safety rods 481, 482, 483, 484, arranged to be brought into and out of position to be engaged by lugs 485, 486, 487, 488 respectively, on the outer eccentric bearings 215, 216, 217, 218. The cams 267, 268 and 311, 312 on their respective shafts 269, 270 are driven from their impression cylinder shafts 19, 20 at a selected speed that will not limit the speed of the printing cylinders, through the gears 489, 490 and 491, 492. Removable studs 493, 494, 495, 496 are provided for holding the studs or rollers 307, 308, 309, 310 from following the peripheries of their cams 311, 312, when so desired.

The surface of the impression cylinder 9 of the second printing unit is kept moist to prevent offsetting thereon from the freshly printed side of the web coming from the impression cylinder 10 of the first printing unit. The dampening device comprises, generally, the fountain 497, the foun-

tain roll 498, the ductor roll 499 and the impression cylinder moisture applying rolls 500.

The electrical control for the press comprises the following elements:

5 The control station 501 for the main motor 72 includes the two "print" switches 502, 503, the "run" switch 504, the "jog" switch 505 and the "stop" switch 506.

10 The control station 507 for the auxiliary motor 73 includes the "run" switch 508, the "jog" switch 509, the "stop" switch 510 and the "reverse" switch 511.

The control station 512 for the auxiliary motor 74 includes the "run" switch 513, the "jog" switch 514, the "stop" switch 515, and the "reverse" switch 516.

15 The main motor clutch magnets are denoted by 517, 518 and their stop switches operated mechanically from the main motor clutches are denoted by 519, 520 respectively; their switches which stop the auxiliary motors 73, 74 by 521, 522 respectively; and the maintaining switches for the hand or automatically operated trip magnets 523, 524 by 525, 526 respectively.

20 25 The auxiliary motor clutch magnets are denoted by 527, 528; the main clutch magnetic relay is denoted by 529 and its contacts by 530, 531; the main motor slow speed relay is denoted by 532, its main motor slow speed contacts by 533, its contacts for maintaining the main motor circuit by 534, and its contacts for the control circuit for the main motor high speed relay 535, by 536. The contacts for the main motor high speed relay 535 are denoted by 537.

30 35 The hand operated switch to run the web at high or low speed when the impression cylinders are operatively disconnected from their design and transfer cylinders, is denoted by 538.

40 The hand operated switches to hold either of the printing units inactive, is denoted by 539, 540.

The auxiliary motor relays are denoted by 541, 542 respectively, the relay 541 being provided with the contacts 543, 544, 545, 546, 547 and the relay 542 being provided with the contacts 548, 549, 550, 551, 552.

45 50 The slow down switches 553 and the main motor magnetic clutch operating switches 554 are all operated from the inner eccentric bearings 219, 220, 221, 222.

55 The web break detector switch is denoted by 555; the color detector switch by 556; the paster detector switch by 557; and the hand switch by 558.

The relay 559 is provided with the contacts 560, 561, 562, and the relay 563 is provided with the contacts 564, 565, 566.

The main motor relay, in connection with the hand operated switch 538, is denoted by 567 and it is provided with the contacts 568, 569, 570.

60 *In operation*

65 The printing plates and packings may be attached to the design cylinders 1, 2, 3, 4 in the usual manner, the switches of the auxiliary motor control stations 507, 512 being used to "jog" or "reverse" the design cylinders to permit the ready attachment of the plates thereto. New blankets may be attached to the transfer cylinders 5, 6, 7, 8 or the cylinders may be cleaned

70 75 and their old blankets prepared, the switches of the said auxiliary motor control stations 507, 512 being also used for this purpose.

The colors are placed in the ink fountains 21, 22, 23, 24 and the ink is fed to the distributing rollers 37, 38, 39, 40, to obtain the proper dis-

tribution for printing. To do this the design cylinders 1, 2, 3, 4, the transfer cylinders 5, 6, 7, 8, the inking mechanisms, and the moistening mechanisms are all operated in unison. The ink is fed by releasing the latch bars 457, 458, 459, 460 from the lever arms 175, 176, 177, 178 respectively, to permit the spring pressed rollers 163, 162, 161, 162, carried by the lever arms 163, 164, 165, 166 respectively, to be swung upwardly into contact with their rotary cams 155, 156, 157, 158, 159, 160, 161, 162 respectively, thereby causing an intermittent forward movement to the roller 15 clutches 29, 30, 31, 32 which rotate the ink fountain rolls 25, 26, 27, 28, step by step. The amount of this movement may be adjusted by turning the hand screws 191, 192, 193, 194.

The moistening mechanism may be prepared by placing water and acid solution in the fountains 45, 46, 47, 48 and transferring the moisture therefrom to the design cylinders 1, 2, 3, 4, through the rolls 49 to 69 inclusive, by running the pairs of design and transfer cylinders of the two printing units.

If necessary, the gum may be removed from the printing plates on the design cylinders 1, 2, 3, 4, the "jog" switches 509, 514 of the auxiliary motor control stations 507, 512 being used for this purpose.

The "run" switches 508, 513 of the auxiliary motor control stations 507, 512 may then be closed to allow the design and transfer cylinders of the two printing units to be run together with their inking and moistening mechanisms, it being understood that the rollers 57, 58, 59, 60 of the moistening mechanisms are properly adjusted for the desired amount of moisture to be applied to the design cylinders 1, 2, 3, 4.

The inking rollers 41, 42, 43, 44 which have been in their raised position out of contact with their design cylinders may then be dropped into contact with the surfaces of the design cylinders by unlatching the hook bars 353, 354, 355, 356 from their pins 365, 366, 367, 368, thus allowing the operating forked bars 369, 370, 371, 372 to drop, bringing their shoulders 394, 395, 396, 397 into engagement with the pins 402, 404, 406, 408 respectively, on the rock levers 409, 410, 411, 412.

The operating forked bars 369, 370, 371, 372 which are connected to the arms 373, 374, 375, 376 of the rock levers pivoted at 377, 378, 379, 380 respectively, are oscillated by the contact of the spring pressed rollers 285, 286, 287, 288 on the lever arms 381, 382, 383, 384 with the faces of the rotary cams 399, 399, 391, 392 on the design cylinder shafts 11, 12, 13, 14.

The rock levers 409, 410, 411, 412 which are fixed to the rock shafts 413, 414, 415, 416, because of their connection between the depending arms 417, 418, 419, 420, rods 421, 422, 423, 424 and depending arms 425, 426, 427, 428 swing the eccentrics 433, 434, 435, 436 on the rock shafts 429, 430, 431, 432, to permit the end plates 437, 438, 439, 440 of the inking roller carriages to drop, thus permitting the inking rollers 41, 42, 43, 44 to be brought into contact with the peripheries of their design cylinders 1, 2, 3, 4 respectively.

The pressman may now examine the plates on the design cylinders 1, 2, 3, 4 to see if the ink and water are functioning properly. He then raises the inking roller carriages, thereby lifting the ink rollers 41, 42, 43, 44 out of contact with the peripheries of their respective design cylinders 75

1, 2, 3, 4. This is accomplished by re-engaging the hook bars 353, 354, 355, 356 with their pins 365, 366, 367, 368 on the operating forked bars 369, 370, 371, 372, thereby raising the operating forked bars into engagement with their pins 401, 403, 405, 407, thus reversing the movement of the rock shafts 413, 414, 415, 416.

During this period of preparing the plates on the design cylinders 1, 2, 3, 4, the design and transfer cylinders of both printing units have been constantly rotated at a slow speed except when the pressman has wished to examine the plates closely by operating the "stop" switches 510, 515 of the auxiliary motor control stations 15 507, 512. It is understood that the pressman may also then operate the "jog" switches 509, 514 of the said stations 507, 512, to bring any particular portions of the plates into ready position for examination.

20 If satisfied with the condition of the plates on the design cylinders 1, 2, 3, 4 of both printing units, the pressman may then close the "run" switches 508, 513 of the auxiliary motor control stations 507, 512 and allow the design and transfer cylinders to run together with their moistening mechanisms, thus continuously keeping the plates on the design cylinders moist.

Should the pressman desire to stop the design and transfer cylinders for a considerable period 30 of time he will, of course, gum the plates on the design cylinders, using the "jog" switches 509, 514 of the auxiliary motor control stations 507, 512, to permit the application of the gum solution over the entire surfaces of the plates.

35 If the pressman finds the plates in condition for printing he will then prepare to print on the blankets of the transfer cylinders 5, 6, 7, 8 of the two printing units so that the blankets will be in condition to print on the web passing 40 around the impression cylinders 10, 9 with a minimum amount of waste. This printing operation is accomplished by swinging the hand levers 223, 224, 225, 226 from their positions "A" to their positions "B", and operating the handles 465, 466, 467, 468. Latch levers 578, 579 hold the lever arms 580, 581, thus releasing the arms 574, 575 from the uprising lever arms 283, 284, so that pressure between the transfer cylinders 5, 6, 7, 8 and their impression cylinders 9, 10 cannot be 50 thrown on when the main motor magnetic clutches 117, 118 are out of engagement. Otherwise, if pressure were thrown on the transfer cylinders 5, 6, 7, 8 of the two printing units while rotating, they might come into contact with the impression cylinders 9, 10 when stationary, thus causing damage to web and press.

The levers pivoted at 582, 583 are connected to levers pivoted at 584, 585, by rods 586, 587 and are operated by the main motor clutches 117, 118, 60 when thrown out of engagement, to place the latch levers 578, 579 in engagement with the lever arms 580, 581 of the rock levers pivoted at 576, 577.

65 In moving the handles 465, 466, 467, 468 of the overthrow levers pivoted at 461, 462, 463, 464, the studs or rollers 473, 474, 475, 476 move the operating forked bars 291, 292, 293, 294 into engagement with their pins 321, 323 and 325, 327 respectively. It will be remembered that these 70 forked bars 291, 292, 293, 294 are moved by their levers pivoted at 299, 300, 301, 302 respectively, through the cams 311, 312 and the studs or rollers 307, 308, 309, 310, thus causing the forked bars 291, 292, 293, 294 to push against their respective pins 321, 323 and 325, 327, carried by the rock

levers 329, 330, 331, 332, thereby moving the inner eccentric bearings 219, 220, 221, 222 of the transfer cylinders through the connections 255, 256, 257, 258. This operation will throw pressure on between the cylinders.

It will be remembered that the cams 267, 268, 311, 312, mounted on the shafts 269, 270 respectively, are timed in relation to each other. These shafts 269, 270 are driven at their lower speed to reduce the strains on the pressure operating mechanism consistent with every day practice and still not limit the printing or cylinder speed of the press.

By returning the handles 465, 466, 467, 468 to their original positions the cylinders will be 15 separated to "pressure-off" positions.

It is only possible to return the hand levers 223, 224, 225, 226 to their positions "A" after pressure has been released, placing both the safety rods 481, 482, 483, 484 and lock bars 337, 338, 339, 340 in non-interfering positions. The safety rods 481, 482, 483, 484 are for the purpose of preventing the operator from operating the pressure mechanisms before the hand levers 223, 224, 225, 226 are in correct position. The lock bars 337, 338, 339, 340 will prevent the hand levers 223, 224, 225, 226 from being moved to position "A" before pressure between the design and transfer cylinders has been released.

It will be observed that the design and transfer cylinders of either one of the printing units can be held in non-printing position indefinitely, without interfering with the make-ready or printing operation of the balance of the press. This is accomplished by inserting either one or 35 more of the studs 493, 494, 495, 496 for preventing the corresponding studs or rollers 307, 308, 309, 310 from following their respective cams 311, 312, as the case may be.

While I have referred specifically to the operating mechanisms for both printing units and their combined coaction and non-coaction with their impression cylinders, still it is to be understood that either pair of the design and transfer cylinders of either printing unit may be made 45 ready or remain inactive, as far as the printing is concerned, for printing a single color, or for printing any combination of two, three or four colors; without affecting the speed or efficient operation of the remainder of the press.

From the above description it will be seen that the pressure between the design and transfer cylinders of both printing units may be obtained and their inking mechanisms may be raised or lowered or held out of contact regardless of the 50 operation of the automatic trip mechanisms.

It will also be observed that the ink fountain feed for each design cylinder of each printing unit may be stopped, started, adjusted or held stopped, regardless of the operation of the automatic trip mechanisms.

Assuming that everything is now ready to start the printing operation:

The design and transfer cylinders of both printing units are running slowly, the ink rollers 65 are raised, the ink fountain feeders are stopped (but there is no pressure between any of the cylinders) and the water rollers are in contact with the design cylinders to prevent oxidation.

While the design and transfer cylinders of 70 both printing units are being prepared for printing, the paper web roll may be placed in position and the web threaded through the press.

The folder may also be tested and the necessary adjustments made to the portion of the 75

press which consists of the web roll drive, the impression cylinders and the folder, without interference with the design and transfer cylinders of both printing units. It will be observed that 5 this portion of the press is driven independently by the main motor 72 and controlled by the station 501 when desiring to do any of the operations mentioned in the last paragraph. The "run" switch 504, the "jog" switch 505, the "stop" 10 switch 506, in connection with the hand operated switch 538 and contactor relay 567 are used during this period. While printing, these units are electrically inactive; the circuit through the contacts 568 operate the main motor; the circuit 15 through the contacts 569 is for maintaining circuit for the contactor relay 567; the circuit through the contacts 570 is for energizing the high speed relay 535 to operate the impression cylinders, the folder, and the web control mechanism at high speed when the hand operated switch 538 is closed.

To start printing the web

It will be kept in mind that the auxiliary motors 25 73, 74 are driving a portion of the press. Change the "run" switch 504 of the main motor control station 501 to the "print" position, closing the switches 502, 503. The current then flows through the switch 502, energizing the slow speed relay 30 532, thus causing the contacts 533, 534, 536 to complete their circuits.

The circuit through the contacts 533 will start the main motor 72 to run "slow speed"; the circuit through the contacts 534 maintains the relay circuit and the circuit through the contacts 536 is closed but inoperative, until the switches 553 close by the movement of the inner eccentric bearings 219, 220, 221 or 222. The closing of the switches 35 502, 503 energizes the relay 529 which is of the time element type, thus causing a delay in closing and completing the circuits through the contacts 530, 531; the circuit through the contact 530 energizes the main clutch magnets 517, 518, thus moving the pins of the magnetic clutches 117, 118 40 into positive engagement with their fast gears 103, 104 respectively, of the main motor drive.

These clutches 117, 118 have about a one-fourth inch movement and in closing, brake the 45 switches 521, 522, 525, 526 and close the main motor clutch switches 519, 520. The circuit through the contacts 530, 531 maintains the relay when the switches 553 or 554 are closed, by movement of the inner eccentric bearings 219, 220 or 221, 222.

The switches 519, 520 are provided for automatically stopping the main motor when the printing ceases. Opening the switches 521, 522 breaks the maintaining circuit through the contacts 545, 550 50 of the relays 541, 542, thus stopping the auxiliary motors 73, 74 and deenergizing the clutch magnets 527, 528.

Opening the switches 525, 526 breaks the circuit through the trip magnets 523, 524, thereby causing the transfer cylinders to move into contact with their design and impression cylinders 55 as hereinbefore set forth.

It will be noted that the switches 519, 520, 521, 522, 525, 526 are mechanically operated by the magnetic clutches 117, 118. Opening the switches 70 525, 526 ensures the main clutches being in positive engagement before pressure can be thrown on between the cylinders. This is important as all of the cylinders must be driven from the main source to ensure correct peripheral speeds.

75 The movement of the inner eccentric bearings

219, 220, 221, 222 when pressure is thrown on, will close the switches 553, 554. The closing of the switches completes the circuit through the contacts 536, thus energizing the relay 535 and closing its contacts 537, thereby causing the main motor to speed up to its fast printing speed. The press may now be considered as printing correctly at high speed and the operator may remove his finger from the "print" switch 502 of the main motor control station 501.

10 The four switches 555, 556, 557, 558 are provided for stopping the printing operation according to requirements. The closing of any one of these switches would operate as follows:

If the web should break, the web brake detector 15 switch 555 would close, thus energizing the trip magnets 523, 524 and causing the trip mechanism to operate. This will open the switches 553, 554. Opening the switches 553 causes the current through the contacts 537 to break, thus slowing down the motor. Opening the switches 554 causes the current to be broken through the magnetic relay 529, thus stopping the current from flowing into the magnetic clutches 117, 118. These 20 clutches 117, 118 move out of driving contact, thus operating the switches 519, 520, 521, 522, 525, 526. The switches 519, 520 break the maintaining circuit through the contacts 534, thus causing the relay 532 to release the contacts and stop the main motor 72.

30 All of the above operations are automatic and are operated in proper sequence. It is now necessary to close the "run" switches 508, 513 of the auxiliary motor control stations 507, 512, to allow the auxiliary motors 73, 74 to "run" if it be 35 desired to keep the printing plates moist. If not, it is necessary to gum the plates.

From the above description it will be seen that it is impossible to operate the auxiliary motors or clutches while the press is being driven by the 40 main motor and the web is being printed.

It will also be seen that means have been provided whereby the web advancing mechanism and the impression cylinders of the two printing units can be stopped, started, and run independently of 45 the design and transfer cylinders and their inking and moistening mechanisms.

It will also be seen that means have been provided whereby the design and transfer cylinders and their inking and moistening mechanisms can 50 be stopped, started, and run independently of the web advancing mechanism and the impression cylinders.

It will also be seen that the pairs of design and transfer cylinders can be stopped, started and 55 run independently of one another as well as independently of the impression cylinders.

The above provisions in a multicolor press enable the independent handling of the parts as above set forth, to cause the press to be brought 60 into its full printing condition in the shortest time and with the least wastage of web material.

While I have illustrated a folder as a part of the web advancing mechanism, it is to be understood that I do not wish to limit myself to 65 this particular mechanism, but wish to cover any mechanism which it may be desired to use.

The parts of the printing press which are shown and described, but not claimed herein, form the subject matter of my copending application filed 70 May 17, 1933, Serial No. 671,451, now Letters Patent No. 1,972,470, dated September 4, 1934; of my copending application filed June 7, 1934, Serial No. 729,365; and my copending application filed June 20, 1934, Serial No. 731,439.

It is also evident that various changes may be resorted to in the construction, form and arrangement of the several parts without departing from the spirit and scope of my invention, and hence I do not intend to be limited to the particular embodiment herein shown and described, but

What I claim is:

1. In a multicolor offset printing press, a plurality of printing units, each comprising a common impression cylinder and pairs of design and transfer cylinders interconnected therewith, their drive, means for separating and means for operatively disconnecting the transfer cylinders from their impression cylinders, and means for driving the design and transfer cylinders independently of their impression cylinders and independently of each other.
2. In a multicolor offset printing press, a plurality of printing units, each comprising a common impression cylinder and pairs of design and transfer cylinders interconnected therewith, their drive, means for separating and means for operatively disconnecting the transfer cylinders from their impression cylinders, and means for driving the impression cylinders independently of their design and transfer cylinders and the design and transfer cylinders independently of each other.
3. In a multicolor offset printing press, a plurality of printing units, each comprising a common impression cylinder and pairs of design and transfer cylinders interconnected therewith, their drive, means for separating and means for operatively disconnecting the transfer cylinders from their impression cylinders, means for driving the design and transfer cylinders independently of their impression cylinders and independently of each other and means for driving the impression cylinders independently of their design and transfer cylinders.
4. In a multicolor offset printing press, a plurality of printing units, each comprising a common impression cylinder and pairs of design and transfer cylinders interconnected therewith, web advancing means, their drive, means for separating and means for operatively disconnecting the design and transfer cylinders from their impression cylinders without disconnecting the impression cylinders and web advancing means, and means for driving the design and transfer cylinders independently of their impression cylinders and the web advancing means and independently of each other.
5. In a multicolor offset printing press, a plurality of printing units, each comprising a common impression cylinder and pairs of design and transfer cylinders interconnected therewith, web advancing means, their drive, means for separating and means for operatively disconnecting the design and transfer cylinders from their impression cylinders without disconnecting the impression cylinders and web advancing means, and means for driving the impression cylinders and web advancing means independently of the design and transfer cylinders, and the design transfer cylinders independently of each other.
6. In a multicolor offset printing press, a plurality of printing units, each comprising a common impression cylinder and pairs of design and transfer cylinders interconnected therewith, web advancing means, their drive, means for separating and means for operatively disconnecting the design and transfer cylinders from their impression cylinders without disconnecting the impression cylinders and web advancing means, and means for driving the impression cylinders independently of the design and transfer cylinders without disconnecting the impression cylinders.

pression cylinders and web advancing means, and means for driving the design and transfer cylinders independently of their impression cylinders and the web advancing means and independently of each other and the impression cylinders independently of the design and transfer cylinders. 5

7. In a multicolor offset printing press, a plurality of printing units, each comprising a common impression cylinder and pairs of design and transfer cylinders operatively connected therewith, their drive, means for separating the transfer cylinders from their design cylinders, means for separating and means for operatively disconnecting the transfer cylinders from their impression cylinders, and means permitting the design and transfer cylinders to be driven independently of the impression cylinders and independently of each other.

8. In a multicolor offset printing press, a plurality of printing units, each comprising a common impression cylinder and pairs of design and transfer cylinders operatively connected therewith, web advancing means, their drive, means for separating the transfer cylinders from their design cylinders, means for separating and means for operatively disconnecting the transfer cylinders from their impression cylinders, and means for driving the design and transfer cylinders independently of the impression cylinders and web 30 advancing means and independently of each other.

9. In a multicolor offset printing press, a plurality of printing units, each comprising a common impression cylinder and pairs of design and transfer cylinders operatively connected therewith, their drive, means for separating the transfer cylinders from their design cylinders, means for separating and means for operatively disconnecting the transfer cylinders from their impression cylinders, and means for driving the impression cylinders independently of the design and transfer cylinders independently of each other. 40

10. In a multicolor offset printing press, a plurality of printing units, each comprising a common impression cylinder and pairs of design and transfer cylinders operatively connected therewith, web advancing means, their drive, means for separating the transfer cylinders from their design cylinders, means for separating and means for operatively disconnecting the transfer cylinders from their impression cylinders, and means for driving the impression cylinders and web advancing means independently of the design and transfer cylinders and the design and transfer cylinders independently of each other. 45 50

55

11. In a multicolor offset printing press, a plurality of printing units, each comprising a common impression cylinder and pairs of design and transfer cylinders operatively connected therewith, their drive, means for separating the transfer cylinders from their design cylinders, means for separating and means for operatively disconnecting the transfer cylinders from their impression cylinders, means for driving the design and transfer cylinders independently of the impression cylinders and independently of each other, and means for driving the impression cylinders independently of the design and transfer cylinders. 60 65

12. In a multicolor offset printing press, a plurality of printing units, each comprising a common impression cylinder and pairs of design and transfer cylinders operatively connected there- 70 75

operatively disconnecting the transfer and impression cylinders, and means for driving the design and transfer cylinders independently of the impression cylinders, said driving means being operable to drive the impression cylinders independently of their design and transfer cylinders and the design and transfer cylinders independently of each other.

24. In a multicolor offset printing press, a plurality of printing units, each comprising a common impression cylinder and pairs of design and transfer cylinders operatively connected therewith, web advancing means, means for driving the printing units as a whole and the web advancing means, means for separating the design and transfer cylinders without operatively disconnecting them, means for separating and means for operatively disconnecting the transfer and impression cylinders, and means for driving the design and transfer cylinders independently of their impression cylinders and the web advancing means and the design and transfer cylinders independently of each other, said driving means being operable to drive the impression cylinders and web advancing means independently of the design and transfer cylinders.

25. In a multicolor offset printing press, a plurality of printing units, each comprising a common impression cylinder and pairs of design and transfer cylinders, their drive, and means for driving the pairs of design and transfer cylinders independently of their impression cylinders and independently of each other.

35 26. In a multicolor offset printing press, a plurality of printing units, each comprising a common impression cylinder and pairs of design and transfer cylinders, web advancing means, their drive, and means for driving the pairs of design and transfer cylinders independently of their impression cylinders and web advancing means and independently of each other.

27. In a multicolor offset printing press, a plurality of printing units, each comprising a common impression cylinder and pairs of design and transfer cylinders, their drive, and means for driving or stopping the pairs of design and transfer cylinders independently of their impression cylinders and independently of each other.

28. In a multicolor offset printing press, a plurality of printing units, each comprising a common impression cylinder and pairs of design and transfer cylinders, web advancing means, their drive, and means for driving or stopping the pairs of design and transfer cylinders independently of their impression cylinders and web advancing means and independently of each other.

29. In a multicolor offset printing press, a plurality of printing units, each comprising a common impression cylinder and pairs of design and transfer cylinders, their drive, means for stopping the design and transfer cylinders without stopping their impression cylinders, and means for stopping the impression cylinders without stopping their design and transfer cylinders.

65 30. In a multicolor offset printing press, a plurality of printing units, each comprising a common impression cylinder and pairs of design and transfer cylinders, web advancing means, their

drive, means for stopping the design and transfer cylinders without stopping their impression cylinders and the web advancing means, and means for stopping the impression cylinders and web advancing means without stopping the design and transfer cylinders.

31. In a multicolor offset printing press, a plurality of printing units, each comprising a common impression cylinder and pairs of design and transfer cylinders, their drive, means for driving the pairs of design and transfer cylinders independently of their impression cylinders and independently of each other, and means for driving the impression cylinders independently of their design and transfer cylinders. 10 15

32. In a multicolor offset printing press, a plurality of printing units, each comprising a common impression cylinder and pairs of design and transfer cylinders, web advancing means, their drive, means for driving the pairs of design and transfer cylinders independently of their impression cylinders and web advancing means and independently of each other, and means for driving the impression cylinders and web advancing means independently of the design and transfer cylinders. 20 25

33. In a multicolor offset printing press, a plurality of printing units, each comprising a common impression cylinder and pairs of design and transfer cylinders, their drive, means for driving or stopping the pairs of design and transfer cylinders independently of their impression cylinders and independently of each other, and means for driving or stopping the impression cylinders independently of their design and transfer cylinders. 35

34. In a multicolor offset printing press, a plurality of printing units, each comprising a common impression cylinder and pairs of design and transfer cylinders, web advancing means, their drive, means for driving or stopping the pairs of design and transfer cylinders independently of their impression cylinders and web advancing means and independently of each other, and means for driving or stopping the impression cylinders and web advancing means independently of the design and transfer cylinders.

35. In a multicolor offset printing press, a plurality of printing units, each comprising a common impression cylinder and pairs of design and transfer cylinders, their drive, means for stopping the design and transfer cylinders independently of their impression cylinders and independently of each other, and means for stopping the impression cylinders without stopping their design and transfer cylinders. 50

36. In a multicolor offset printing press, a plurality of printing units, each comprising a common impression cylinder and pairs of design and transfer cylinders, web advancing means, their drive, means for stopping the design and transfer cylinders independently of their impression cylinders and the web advancing means and independently of each other, and means for stopping the impression cylinders and web advancing means without stopping the design and transfer cylinders.

HOWARD M. BARBER.
